UNITED STATES PATENT OFFICE.

SAMUEL HERMANN, OF CINCINNATI, OHIO.

DESIGN FOR A CLAMP OR LOOP FOR TRUNK-STRIPS.

SPECIFICATION forming part of Design No. 15,071, dated June 17, 1884.

Application filed November 12, 1883. Term of patent 7 years.

To all whom it may concern:

Be it known that I, SAMUEL HERMANN, a citizen of the United States, and a resident of Cincinnati, in the county of Hamilton and State 5 of Ohio, have invented and produced a new and original Design for a Clamp or Loop for Trunk-Strips and other Articles, of which the following is a specification, reference being had to the accompanying drawings, forming part 10 thereof.

Figures 1, 2, and 3 of the drawings represent the clamp having different ornaments. Fig. 4 represents a transverse section of one 15 of the trunk-strips and one edge of the loop, showing its relation to the strip and the trunk.

The loop consists of two twigs, branches, or bars, A A', representing short cuttings of a vine or twig of some bush or tree, and these branches cross the strip *a* from side to side, 20 and at or near the center of the strip they cross each other, constituting a cross, the ends of the branches of which extend a short distance beyond the edge of the trunk-strip, and ordinarily will curve down, as shown in Fig. 4. 25 In the angles formed by the crossing branches or bars which are in a line with the length of the strip are formed extensions B, representing fruit, floral, or other desired designs.

These extensions B, as before stated, may represent either fruit, flowers, vegetables, or any other ornamental design which may be desired, the underlying principle of the design being the crossing pieces, branches, or bars, and an ornament of any desired description formed in the angles aforementioned. When desired, ornaments are to be placed in those angles also which are on a line of direction transverse to the length of the strip. This loop is ornamental, and answers every purpose for which trunk-strip loops are designed. As 30 regards the main feature of this design, it is 35 immaterial whether the clamp or loop, when viewed at any of its edges, be flat or curved.

What I claim as new and original is as follows:

1. A design for loops or clamps, consisting of the two crossing branches or bars A A', substantially as specified.
2. A design for loops or clamps, consisting of two crossing branches or bars, A A', having ornamental extensions B in the angles, as 40 shown and described.

SAMUEL HERMANN.
